(57) **CLAIM**

The ornamental design for a massaging device, as shown and described.

DESCRIPTION

FIG. 1 is a perspective view of a massaging device showing our new design thereof;

FIG. 2 is a rear view of the massaging device shown in FIG. 1;

FIG. 3 is a front view of the massaging device shown in FIG. 1;

FIG. 4 is a first side view of the massaging device shown in FIG. 1;

FIG. 5 is a second side view of the massaging device shown in FIG. 1;

FIG. 6 is a top view of massaging device shown in FIG. 1; and, FIG. 7 is a bottom view of massaging device shown in FIG. 1. Elements shown in broken lines show environmental structures of the massaging device and form no part of our design.
